HONING MACHINE

Albert M. Johnson, Rockford, Ill., assignor to
 Barnes Drill Co., Rockford, Ill., a corporation
 of Illinois

Application July 8, 1936, Serial No. 89,561

20 Claims. (Cl. 51—34)

The invention relates to honing machines of the type in which a generally cylindrical abrasive tool or hone is rapidly reciprocated, with or without rotation of the tool, for dressing cylindrical surfaces to a true contour and smooth finish, and it has particular reference to a honing machine in which the tool is reciprocated by hydraulic means.

In machines of the above character as heretofore constructed, the tool carrying spindle is journaled in a reciprocatory head or carriage supported and guided by ways on the frame of the machine. Reciprocation of the tool spindle is effected by reciprocating the spindle head by means of a hydraulic cylinder and piston mechanism which ordinarily has one or more operating cylinders mounted on the frame and the piston or pistons rigidly secured to the head. For rotating the spindle, there is a drive shaft usually rotatably anchored in the head and reciprocable therewith, a gear train in the head drivingly connecting the shaft and spindle. With this construction the weight of the reciprocating parts is necessarily quite large.

One of the most important requirements for precision honing is that the tool be reciprocated smoothly and rapidly and with substantially no lag at either end of the stroke. To enable the machine to meet these requirements and to withstand the shocks and strains imposed by the relatively large mass of the reciprocating parts, the framework and other elements of the machine must be of exceptionally heavy and rigid construction, which, of course, adds to the cost of the machine. The construction of the spindle head and the machining of the ways, which must be particularly true and accurate, also represents a substantial item in the cost of building the machine.

With the foregoing in view, one object of the invention is to provide an improved honing machine in which, by reason of the novel arrangement of the various elements and the simplified construction thereof, the weight of the reciprocating parts is reduced to a minimum and the machine is rendered capable of being manufactured at a relatively low cost. The above and other objects are attained through the provision of a honing machine in which the spindle carriage is dispensed with entirely, the spindle itself extending into and through the operating cylinder and carrying the piston by which reciprocation is effected.

Another object is to provide an improved honing machine having a hydraulically reciprocated hone and embodying means of an advantageous

character for positively limiting the working stroke of the hone to effectually prevent overrun at either end of the stroke.

Another object is to provide an improved control mechanism for controlling the reciprocation of the honing tool, which mechanism is of simple and rugged construction and which is capable of extremely accurate adjustment.

Still another object is to provide an improved electrical control system for a honing machine whereby the various operations of the machine may be controlled through the medium of conveniently located push buttons.

A further object is to provide improved short stroking means by which the operative effect of the honing tool may be concentrated at selected areas on the work to remove high spots, taper, or the like.

Further objects and advantages will be apparent from the following detailed description of the preferred embodiment selected for illustration in the accompanying drawings. It will be understood, however, that various changes in form, construction and arrangement of the parts may be made by those skilled in the art without departing from the spirit and scope of the invention as expressed in the appended claims.

Referring to the drawings:

Figure 1 is a fragmentary side elevational view of a honing machine embodying the features of the invention.

Fig. 2 is a transverse sectional view taken along the line 2—2 of Fig. 1.

Fig. 3 is a vertical sectional view taken along the line 3—3 of Fig. 2.

Fig. 4 is a detail view of the control rod actuating element.

Fig. 5 is a sectional view of the short stroking mechanism taken along the line 5—5 of Fig. 2.

Fig. 6 is a schematic representation of the electrical control system of the machine.

The machine selected to illustrate the invention is of the vertical type having a frame structure including a column head or housing 7 mounted on the top of an upright column 8. Preferably, the head 7 is in the form of a unitary, hollow casting of generally rectangular cross section and is provided with a forwardly projecting portion in overhanging relation to the side of the column 8. In the preferred form, the various operating and control elements of the machine are enclosed in or supported by the head which materially simplifies manufacture of the machine.

The operating elements of the machine include a tool carrying member in the form of a rota-

table and reciprocable spindle 9 for carrying the tool into operative engagement with the work, which latter may be supported in any suitable manner adjacent the side of the column 8. The 5 tool spindle 9 is supported in the overhanging portion of the head 7 for reciprocation in a substantially vertical plane. At its lower end, the spindle carries a tool holding chuck 10 for floatingly supporting a conventional honing tool 10 (not shown). Power is applied to the spindle through the medium of suitable mechanical and hydraulic drive mechanisms in the head 7 and driven, in the present instance, by an electric motor 11 mounted on a bracket 12 projecting 15 rearwardly of the head.

As herein shown, the drive mechanism for reciprocating the spindle is of the hydraulic type and includes a vertically disposed elongated operating cylinder 13 enclosed in the projecting portion of the head 7. To simplify the construction of the machine and to reduce the weight of the reciprocating parts to a minimum, the tool spindle itself is extended axially through the cylinder and is provided with a piston 14 operable in the cylinder. Pressure fluid is introduced into opposite ends of the cylinder alternately through suitable ducts 15 (Fig. 1) communicating respectively with the upper and lower ends thereof.

In the preferred form of the machine, the cylinder 13 is cast integrally with the head 7 and is held rigid therewith by a web 16 joining the upper end of the cylinder and the side walls of the head as shown in Fig. 3. Preferably, the cylinder terminates substantially below the top wall of the head leaving sufficient space therein for the spindle rotating mechanism and control instrumentalities which cooperate with the projecting upper end of the tool spindle. The ends of the cylinder are closed by suitable cylinder heads 17 and 18 which also provide sliding bearing supports for the tool spindle. As herein shown, the cylinder head 17 is threaded into the upper end of the cylinder and cylinder head 18 is bolted or otherwise secured to the lower end thereof. To seal the cylinder against the escape of pressure fluid, packing glands 19 are provided for each cylinder head, the cylinder being counterbored for this purpose so as to provide suitable seats 19a against which the glands are clamped. Thus, it will be seen that the spindle 9 is effectually supported and guided for reciprocation axially of the cylinder 13 and at the same time is free to rotate in the bearings provided by the cylinder heads.

With the above arrangement, the reciprocatory spindle head or carriage heretofore required is entirely dispensed with and only the tool spindle 9 and the tool itself are reciprocated. The weight 60 of the reciprocating parts of the machine is thus reduced to a minimum permitting the use of simpler and less expensive construction without sacrifice of durability or accuracy. Moreover, the number of parts required for the machine is 65 materially reduced with corresponding reductions in the cost of manufacturing the same.

Pressure fluid for reciprocating the tool spindle 9 may be derived from any suitable source such as a pump 20 which, as herein shown, is directly 70 coupled with the drive shaft 20a of the motor 11. The pump 20 has the usual intake duct 21 for drawing fluid from a storage reservoir or sump 21a which, for convenience, may be enclosed within the head 7. Fluid under pressure is discharged through a pressure duct 22 leading to

a reversing valve 23 which directs the fluid alternately to the upper and lower ends of the cylinder 13. Any suitable type of reversing valve may be employed such as the rocking type valve illustrated in Figs. 1 and 2 which has valve stem 24 5 operable to reverse the pressure line connections when rocked through a relatively small angle. Operation of the reversing valve is effected automatically by control mechanism to be described hereinafter.

The mechanism for rotating the tool spindle 9 comprises, in the present instance, a drive shaft 25 supported in a substantially horizontal position adjacent the upper end of the head 7 in suitable bearings 26 and 27 with one end of the shaft projecting rearwardly of the head. The shaft has a suitable driving connection with the motor 11, as, for example, a V-belt 28 operating over pulleys 29 and 30 carried on the projecting end of the shaft 25 and the motor shaft 20a, 20 respectively. To provide for rotating the tool spindle at different speeds, the pulleys 29 and 30 may conveniently be of the stepped cone type. If additional speed changes are required, the pulleys may be readily interchanged with others 25 of the desired ratio.

Fast on the inner end of the shaft 25 is a bevel gear 31 meshing with a crown gear 32 having a splined driving connection with the tool spindle 9. The crown gear is aligned axially with the spindle and is journaled in a bearing 34 formed in or suitably secured to the top wall of the head 7. Thus, the spindle may reciprocate freely relative to the crown gear while being rotated thereby, the splined portion of the spindle being of sufficient length to maintain the driving connection throughout the entire stroke. To protect the bearing surfaces from dust or grit, the projecting end of the spindle is enclosed in an elongated, hollow guard 35 mounted on the top of the housing.

Suitable means is provided for engaging and disengaging the driving shaft 25 and the motor 11 so that the rotation of the tool spindle may be interrupted without necessitating stopping 45 of the motor. As herein shown, this means is in the form of a belt tensioning device and includes a roller 36 carried by an arm 37 pivotally mounted on the rear wall of the head 7. The roller is disposed intermediate the pulleys 29 and 30 and in a position to place the belt 28 under tension when the free end of the arm 37 is moved 50 downwardly from its normal position.

Movement of the arm 37 to engaging or disengaging positions is effected through the medium of a horizontally disposed rock shaft 38 supported at one side of the housing 7 in front and rear bearings 38a and 38b. A crank 39 fast on the rear end of the shaft is operatively connected with the free end of the arm 37 by a 60 pin 40 operating in a suitably formed slot in the arm whereby movement of the shaft is transmitted to the arm. At the other end of the rock shaft 38 is a crank arm 41 from which depends a manual actuating lever 42 by which the shaft 65 may be conveniently rocked to engage or disengage the drive mechanism. A coiled spring 43 encircling the shaft and interposed between the bearing 38a and a collar 41a fast on the shaft urges crank 39 into engagement with the end 70 of the bearing and thus tends to frictionally maintain the shaft and tensioning device in either set position.

The control mechanism for operating the reversing valve 23 to control the reciprocating cycle 75

of the machine is of simple and rugged construction and, by reason of the improved combination and arrangement of the parts, is susceptible of extremely accurate adjustment. Referring to 5 Figs. 2 and 3, the control mechanism includes a control rod 43 disposed at one side of and substantially parallel to the axis of the tool spindle 9. The control rod is supported for endwise sliding movement in suitable bearings formed respectively in the bottom wall of the head 7 and in a bracket 44 projecting inwardly from a side wall of the head. Mounted at spaced points on the control rod are a pair of limit stops 45 and 46 set to define the extreme limits of the spindle 10 stroke. An intermediate stop 47 cooperates with the stop 46 to define the limits of the working stroke of the spindle.

To provide for the accurate positioning essential for precision honing, the stops 45, 46 and 47 20 are threaded onto the control rod. Suitable means are provided for locking the stops in set position to prevent accidental displacement. Stop 46, which defines the extreme upper limit of the spindle stroke, will ordinarily require adjustment only to compensate for wear of the 25 cooperating parts and the locking means for this stop may conveniently take the form of a locking screw 48. Stops 46 and 47, however, define the working stroke of the spindle and will require 30 adjustment whenever the class of work operated on by the machine is changed. To facilitate such adjustment, the locking means for these stops preferably comprises locking nuts 49 and 50 threaded onto the control rod adjacent the respective stops. Thus the stops 46 and 47 may 35 be quickly and easily adjusted and locked in place to define precisely the working stroke required for a particular class of work.

As herein shown, (Fig. 3) the stops 45, 46 and 40 47 are generally disk shaped in form and are positioned for engagement by an actuator 51 carried by the tool spindle 9 and reciprocable therewith. In the preferred form, the actuator 51 comprises a hollow cylindrical member rotatably supported by anti-friction bearings 53 on a 45 collar 54, the member being counterbored at each end to receive the bearing race rings. The collar 54 is mounted on a reduced portion of the spindle and is clamped against a shoulder 55 formed thereby through the medium of a nut 56 threaded onto the spindle which holds the collar rigid with the shaft. Thus, while the tool 50 spindle and collar are rotating, the actuator remains stationary for engagement with the stops 55 on the control rod. Endwise movement of the actuator 51 relative to the collar 54 is effectually prevented by employing bearings of the pre-loaded type, thus eliminating all endwise play of the actuator.

To enable the actuator 51 to pass the intermediate stop 47 when the tool spindle 9 is advanced from its withdrawn or starting position to working position, the actuator is provided with a longitudinally extending cam groove 57 (Fig. 2) 50 on the side adjacent the control rod 43. One wall of the cam groove, in the present instance the left hand wall as viewed in Fig. 4, is substantially parallel to the axis of the actuator, while the other wall is inclined relative thereto 55 so that the upper end of the groove is of just sufficient width to permit the actuator to pass the stop when it is rotated to a predetermined passing position and the lower end of the groove is of sufficient width to receive the stop when the 60 actuator is in either its passing position or its

normal position. Thus when the spindle is initially advanced from starting position, the stop 47 is engaged by the bottom portion of the cam groove and the actuator is enabled to pass the intermediate stop 47 without shifting the control 5 rod. In passing, of course, the actuator is rotated to its passing position by the cam action of the stop but is immediately and automatically returned to normal position as will appear presently. 10

After stop 47 is passed, the advance of the tool spindle continues until the actuator engages the limit stop 46 to shift the control rod 43 and operate the reversing valve 23. The spindle is then moved upwardly until the actuator engages the 15 intermediate stop 47 which it will do by reason of the fact that it is in normal position with the upper end of the cam groove 57 out of alignment with the stop. The tool spindle will thus be reciprocated in its working stroke as determined by the positioning of the stops 46 and 47, which enable the actuator carried by the spindle to shift the control rod at each end of the stroke. 20

To terminate the working stroke of the spindle and return it to the withdrawn position, the 25 actuator 51 is rotated to a position in which the upper end of the cam groove is aligned with the stop 47. The spindle thus continues its upward movement until the actuator engages the upper limit stop 45 and thereby operates suitable control mechanism effective to stop the machine. 30

Movement of the actuator 51 from normal to passing position is effected by suitable control means enclosed in the head 7. To this end, the side of the actuator opposite the cam groove 57 35 is formed with longitudinally extending teeth 58 adapted to mesh with the teeth of a segmental gear 59 mounted in the side of the housing adjacent the tool spindle. As herein shown, the gear 59 is of substantial length so as to constantly mesh with the actuator as the latter reciprocates with the tool spindle. Thus, the actuator is under control of the gear 59 at all times. 40

As will be seen by reference to Fig. 3, the segmental gear 59 is fast on a vertical shaft 60 rotatably supported in spaced bearings formed in brackets 61 on the side of the wall of the head 7. The shaft and gear are held in a normal position by means of a coiled spring 62 encircling 45 the shaft, one end of the spring being anchored to a collar 63 pinned to the shaft, the other end being anchored to a sleeve 63 loosely mounted on the shaft but held against rotation relative thereto by a pin 64 (Fig. 2) threading into the 50 front wall of the head and engaging one of the several apertures provided in the sleeve for this purpose. The tension of the spring 62 may be readily adjusted by withdrawing the pin 64 from engagement with the sleeve and rotating the 55 sleeve until the desired tension is obtained, whereupon the sleeve is locked in place in the usual way. A second collar 65 fast on the shaft holds the sleeve in position when the pin 64 is temporarily withdrawn from engagement therewith and also prevents the sleeve from binding 60 on the shaft.

Rotation of the shaft 60 and segmental gear 59 is effected in the present instance by a solenoid 66 (Fig. 2) having an armature 67 arranged 70 for movement transversely of the axis of the shaft. As herein shown, the solenoid is mounted on an outside wall of the head 7 and the armature 67 is operatively connected with the shaft by a jointed link 68 pivotally connected with a 75

crank arm 69 fast on the lower end of the shaft. The solenoid 66, on being energized, draws in the armature 67 and thus rotates the shaft 60 and gear 59 in a clockwise direction as viewed in Fig. 2. The actuator 51 is thereby rotated in the opposite direction to the passing position in which the cam slot 57 is aligned with the intermediate stop 47. When the solenoid becomes deenergized, the shaft, segmental gear and actuator are returned to the positions shown in Fig. 2, that is, their normal positions, under the influence of the spring 62.

The engagement of the actuator 51 with the upper limit stop 45 or the intermediate stop 47 shifts the control rod 43 from its lower to its upper position. In order to maintain the control rod in this position during the downward stroke of the tool spindle, means is provided for substantially counterbalancing the weight of the rod. As herein shown, the counterbalancing means comprises a compression spring 52 (Fig. 3) encircling the control rod and interposed between the lower bearing of the rod and a collar 53^a fast on the rod.

It will be observed that, with the above construction, the control rod 43 is movable only endwise, and that the actuator 51 mounted directly on the spindle is rotated to provide the skip-stop action by which the tool spindle is moved to and from the operating position. This is an important feature of the invention as it permits the use of simple, rugged stops which can be threaded onto the control rod to provide for precision adjustment of the spindle stroke. It also results in a simplification of the associated parts and apparatus and permits the control rod to serve the additional function of positively limiting the movements of the tool spindle to prevent overrun at the ends of the working stroke as will be described in detail hereinafter.

The shifting of the control rod 43 is utilized to operate the reversing valve 23 and thereby control the reciprocation of the spindle. To this end, the control rod is formed with rack teeth 70 (Fig. 3), engaging with a pinion 70^a (Fig. 2) fast on the end of a cross shaft 71, which is journaled in an elongated bearing 71^a formed on the side wall of the head 7. The shaft 71 carries a crank arm 72 connected by a link 72^a with a second crank arm 73 fast on the rocking valve stem 24. Thus, when the cross shaft is rocked incident to the shifting of the control rod by the spindle carried actuator, the valve stem is moved from one position to the other to direct pressure fluid to the upper and lower ends of the cylinder 13 alternately.

Due to inherent operating characteristics of the hydraulic mechanism, it is impractical to obtain absolutely uniform stroking of the tool spindle by means of the reversing valve alone, the spindle ordinarily overrunning somewhat at each end of the stroke. This overrun affects the accuracy of the work and hence, is objectionable in precision honing. To avoid this difficulty, suitable means is provided for positively stopping the movements of the tool spindle exactly at the prescribed limits of its working stroke, regardless of the length of the stroke.

In its preferred form, the stop means comprises suitable stop members or bumpers 74 and 75 stationarily supported in the head 7 and positioned for engagement by the upper limit stop 45 and the collar 53^a respectively, as the control rod 43 is shifted up or down by the actuator 51 engaging the stops 46 and 47, and coincidentally with

the tool spindle reaching the limits of its stroke. The bumpers 74 and 75 are preferably constructed of hard rubber or other resilient material to enable them to absorb the shock incident to stopping the tool spindle and to render the machine quiet in operation. Thus, movement of the control rod and the tool spindle is positively stopped with a minimum of shock and jar, and overrun of the spindle is effectually prevented, thereby enabling the machine to operate with the accuracy essential for precision honing.

The movement of the cross shaft 71 is further utilized to operate an electric stroke counter 77, preferably of the type disclosed in my prior Patent No. 1,945,045, granted January 30, 1934. As herein shown, (Fig. 1), the stroke counter is mounted on the front wall of the head 7 with its operating arm 78 extending generally rearwardly toward the cross shaft. A crank arm 79 fast on the cross shaft is arranged to operatively engage the operating arm 78 incident to the rocking of the cross shaft and thus register the number of spindle strokes on the stroke counter. As shown in Fig. 6, the stroke counter 77 is provided with the usual normally open switch 80 adapted to be closed upon the registration of the number of strokes for which the counter is set. The switch is arranged to initiate the operation of the solenoid 66 for causing the withdrawal of the tool spindle to its starting position.

Suitable means is provided for automatically stopping the machine and for resetting the stroke counter incident to the return of the tool spindle to starting position at the end of an operating cycle. As herein shown, (Figs. 1 and 2) this means includes a stop bar 81 extending generally parallel to the axis of movement of the tool spindle and slidably supported for endwise movement by brackets 82 and 83 on the front wall of the head. An operating arm 84 fast on the bar projects rearwardly therefrom and into the head through a slot 85 provided for this purpose. The arm 84 is positioned so as to rest on the actuator 51 when the tool spindle is in the starting or withdrawn position thereby supporting the weight of the bar. When the spindle is advanced to working position the support for the bar is withdrawn and the bar moves under its own weight downwardly until a stop collar 86 carried by the bar engages the bracket 83. The stop bar remains in its lower position throughout the operating cycle of the machine.

The stopping of the machine is effected by the stop bar through the medium of a switch 87 (Figs. 1, 2 and 6) arranged, when operated, to interrupt the energizing circuit of a solenoid 88 which controls a main switch 89 through which current is supplied to the motor 11. To this end, the bar carries an actuating member 90 arranged to cooperate with a switch arm 91 by which the switch 87 is actuated, the arrangement being such that the switch is opened when the bar is in its upper position and closed when in its lower position. Resetting of the stroke counter 77 is effected by the movement of the stop bar from the lower to the upper position through the medium of a rack 92 on the bar engaging with a resetting pinion 93 on the operating shaft of the counter.

Manually operable means is provided for varying the normal operating stroke of the tool spindle whereby the action of the honing tool may be concentrated at selected areas of the work to remove high spots or the like. In this operation,

which is commonly referred to as "short stroking", the tool is caused to travel over the selected area in relatively short, quick strokes. To this end, the manually operable means is 5 arranged for operating the reversing valve 23 independently of the automatic control mechanism hereinbefore described.

Referring more particularly to Figs. 2 and 5, the manually operable short stroking means in 10 its preferred form comprises a pair of sleeve members 94 and 95 arranged end-to-end and yieldably coupled by a coiled spring 96 encircling and anchored at opposite ends to the respective members. The coupled sleeves are loosely mounted on 15 the cross-shaft 71, a limited sliding movement axially of the shaft being permitted by the positioning of a retaining collar 97 fast on the end of the shaft. The member 94 is provided on its inner face with a clutch element 98 adapted to 20 engage a complementary clutch element 99 formed on the hub of the crank arm 72 which, as previously explained, is fast on the shaft 71. A hand lever 100 secured to the member 95 provides a convenient means of rotating the 25 coupled members.

It will be apparent that, when the clutch elements 98 and 99 are engaged, the reversing valve 23 may be operated to either of its positions by manipulation of the hand lever 100 thus permitting 30 the attendant to control the stroke of the tool at any point in the work. When it is desired to "short stroke" at a point intermediate the ends of the normal working stroke, the clutch is engaged and the hand lever 100 is oscillated to 35 reverse the valve 23 at the proper intervals. For "short stroking" in areas adjacent the ends of the normal working stroke, the clutch elements are engaged and a steady pressure is applied to the hand lever 100 tending to move the control 40 rod to its upper or lower position as required. Thus for "short stroking" at the lower end of the normal stroke the hand lever is forced to the right as viewed in Fig. 1, thereby tending to raise the control rod to its upper position and 45 operate the valve 23 so that pressure fluid is supplied to the upper end of the cylinder 13 before the spindle reaches the upper limit of its working stroke. The hand lever is turned in the other direction to "short stroke" at the upper end of the normal stroke, valve 23 being operated to introduce pressure fluid into the operating cylinder before the spindle reaches the lower limit of its stroke. The amount of pressure applied to the hand lever determines the 50 short stroking cycle by regulating the tension of the spring 96 through which the control rod shifting force is applied. Moreover, by reason of the yieldable connection of the clutch sleeve 94 and lever sleeve 95, the shock resulting from the 55 engagement of the actuator 51 with the limit stops as the spindle moves toward its normal limit position is absorbed by the spring 96 instead of being transmitted to the hand lever 100. The attendant is thus enabled to control the 60 short stroking operation easily and with greater accuracy.

Referring now to Fig. 6, the electrical control system of the machine is especially arranged with a view to simplifying the work of the attendant 70 and, at the same time, providing efficient and reliable operation. As herein shown, current for operating the motor 11 and the various solenoids of the control system is taken from a three conductor power line 101. Current is supplied to the 75 motor 11 through a main switch 89 when the

switch is closed in response to the energization of the solenoid 88. The solenoid is initially energized to start an operating cycle of the machine by the momentary closure of a push button operated starting switch 102.

To continue the operation of the machine through a complete cycle comprising, for example, an approach stroke wherein the tool spindle is advanced from starting to operating or working position, a plurality of working strokes, and 10 a return stroke to withdraw the spindle to starting position, means is provided for maintaining the solenoid 88 energized under control of the stroke counter 77.

To this end, the solenoid is provided with a 15 holding circuit, including normally closed push button switches 103 and 104, the stop switch 87, closed when the tool spindle is advanced from the starting position, and a switch 105 closed by the solenoid 88 concurrently with the closure of the 20 main switch 89. In the normal operation of the machine, stroking of the tool spindle continues until the solenoid 88 is energized under control of the stroke counter 77 to permit the spindle to return to starting position and open the switch 25 87. Upon the opening of the switch 87, solenoid 88 becomes deenergized and opens the main switch 89 thereby stopping the motor 11.

In case of emergencies, the motor 11 may be stopped independently of the stroke counter by 30 the actuation of the stop switch 103. This opens the solenoid holding circuit with the same results as the opening of the switch 87.

When setting up the work and when first advancing the tool into engagement therewith, it 35 is desirable to advance the tool spindle in relatively short steps without initiating an operating cycle of the machine, this operation being commonly referred to as "inchng". With this in view, an "inchng" push button has been provided for opening the normally closed switch 104 and simultaneously closing a normally open switch 106. Closure of the switch 106 energizes the solenoid 88 to start the motor 11 in the usual way. Locking up of the solenoid is prevented, 40 however, by reason of the opening of switch 104 which prevents the completion of the holding circuit. Thus, the motor is operated and the tool spindle is advanced only while the "inchng" push button is actuated, the operation ceasing as soon 45 as the push button is released. The attendant is thus enabled to advance the tool into the work in easy stages.

The control system also includes means for varying the stroking cycle for which the stroke 50 counting apparatus is set to increase or decrease the number of working strokes of the tool. As will be seen by reference to the drawings, the switch 80 of the stroke counter, when closed, completes a circuit through a normally closed switch 107, for energizing an auxiliary solenoid 108. Solenoid 108 in turn closes a switch 109 to complete an energizing circuit for the solenoid 88 which actuates the control mechanism to terminate the operation of the machine with the tool spindle withdrawn to starting position. Since the switch 107 is in series with the switch 80, opening of the first mentioned switch will prevent the energization of the solenoid 108 and thus 55 increase the number of strokes over the number set on the counter. A normally open switch 110 is connected in parallel with the counter switch 80, so that when a smaller number of strokes is desired than the number set up on the counter, 60 65 70 75

energization of the solenoids 108 and 66 may be effected independently of the counter switch.

It will be apparent from the foregoing description that the invention provides a honing machine of improved and simplified construction which is relatively inexpensive to manufacture. The weight of the reciprocating parts is reduced to a minimum thereby materially improving the operating efficiency of the machine by enabling it to function with extreme accuracy at relatively high speeds. Accurate operation is facilitated by providing improved means for positively limiting the working stroke of the tool spindle to prevent overrun of the tool at either end of its stroke. Moreover, the control mechanism has been improved to provide for precision adjustment and, at the same time, to obtain a simple and rugged construction which is efficient and reliable in operation.

20 I claim as my invention:

1. In a honing machine having a rotatable and reciprocable tool carrying spindle, in combination with a frame structure, an elongated cylinder supported on said frame structure coaxially with the spindle, said spindle extending entirely through the cylinder and having sliding bearing supports at opposite ends thereof, a piston element on the spindle within said cylinder, means for reciprocating the spindle including a source of pressure fluid and valve means for directing the pressure fluid into opposite ends of said cylinder alternately, and an actuator carried by said spindle above the piston element cooperating with control means on said frame structure for actuating said valve means.

2. In a honing machine having a rotatable and reciprocable tool carrying spindle, in combination, means for rotating the spindle, hydraulic means for rapidly reciprocating the spindle simultaneously with its rotation, valve means for controlling said hydraulic means and operative to determine the approximate limits of movement of the spindle, and control mechanism for actuating said valve means and operative to terminate the movements of the spindle exactly at the prescribed limits of its movements, said control mechanism including an actuating member mounted on the spindle for reciprocation therewith, a control rod slidably supported for endwise movement at one side of the spindle, a pair of spaced elements mounted on said control rod in position respectively to be operatively engaged by said actuating member as the spindle approaches the limits of its movement whereby the control rod is shifted in the direction of movement of the spindle, means operated by the control rod in its movement for actuating said valve means, and means engageable with said control rod upon the spindle reaching the prescribed limits of its movements for positively stopping the spindle.

3. In a honing machine, in combination, a rotatable and reciprocable tool carrying spindle, means for rotating the spindle, means for rapidly reciprocating the spindle simultaneously with its rotation, and controlling means for said reciprocating means operative to confine the reciprocating movements of the spindle within accurately defined limits, said controlling means including an actuating member mounted on the spindle, a rod slidably supported for endwise movement substantially parallel to the path of movement of the spindle, a pair of spaced elements mounted on said rod in position respectively to be engaged by said actuating member as the spindle approaches the limits of its movement whereby the rod is shifted

in the direction of movement of the spindle, and stop means coacting with said rod to positively stop the spindle exactly at its prescribed limits of movement.

4. In a honing machine, in combination, a reciprocatory tool carrying spindle having a working stroke of substantially shorter length than the maximum stroke of the spindle, hydraulic means for rapidly reciprocating said spindle in its working stroke, and control means effective to control said hydraulic means and to positively prevent the spindle from overrunning the limits of its working stroke, said control means including a member adapted to be shifted alternately in opposite directions by said spindle as the spindle approaches the limits of its working stroke, and resilient means engageable by said member incident to its shifting for stopping spindle movement exactly at the prescribed limits of the working stroke and for absorbing the shock incident to such stopping.

5. Control mechanism for a honing machine having a reciprocatory tool carrying spindle comprising, in combination, an actuating member carried by the spindle and reciprocable therewith, a control rod supported for endwise movement parallel to the axis of movement of the spindle, a pair of limit stops mounted on said rod in spaced relation, said stops being positioned on opposite sides of said actuating member and alternately engageable thereby to define the extreme limits of spindle movement, an intermediate stop mounted on said rod between said limit stops and engageable by said actuating member to define with one of said limit stops the working stroke of the spindle, said intermediate stop and one of said limit stops having threaded connections with said rod whereby precision adjustment of the stops relative to each other and to said actuating member may be effected, and means for shifting said actuating member relative to the spindle to enable the member to pass said intermediate stop without operatively engaging the same.

6. A control mechanism for a machine tool having a reciprocating tool carrying spindle, comprising, in combination, a control element supported for movement parallel to the axis of movement of the spindle, a pair of limit stops mounted on said element in spaced relation, an intermediate stop mounted on said element between said limit stops, an actuator carried by said spindle adapted to coact with said stops to shift said element and thereby control the reciprocation of the spindle, said actuator including a member movable into one position in which it is effective to operatively engage a limit stop and said intermediate stop to define the working stroke of the spindle and into another position in which it is effective to engage only said limit stops to define the extreme limits of spindle stroke, and means for moving said member from one position to the other.

7. A control mechanism for a machine tool having a reciprocatory tool carrying spindle, comprising, in combination, a control element supported for movement parallel to the axis of movement of the spindle, a pair of limit stops mounted on said element in spaced relation, an intermediate stop mounted on said element between said limit stop, and an actuator carried by said spindle adapted to coact with said stops to shift the control element and thereby control the reciprocation of the spindle, said actuator being effective to operatively engage the intermediate stop when the spindle is moving in one direction.

and to pass the intermediate stop without shifting the control element when the spindle is moving in the other direction.

8. A control mechanism for a machine tool having a rotatable and reciprocable tool carrying spindle, in combination, a control rod supported for endwise sliding movement parallel to reciprocating path of the spindle, means operatively associated with said control rod for controlling the reciprocation of the spindle, a pair of limit stops mounted on said rod in spaced relation, and an actuator mounted directly on said spindle and reciprocable therewith positioned to coact with said stops in the reciprocation of the spindle to 15 actuate said control rod.

9. A control mechanism for a machine tool having a reciprocating tool carrying spindle comprising, in combination, a control rod supported for movement parallel to the axis of movement of said spindle, a pair of limit stops mounted on said rod in spaced relation, an intermediate stop mounted on said rod between said limit stops, and an actuator carried by said spindle operative to engage said stops to shift the control rod and thereby control the reciprocation of the spindle, said actuator being movable relative to the spindle to a position in which it is ineffective to engage said intermediate stop.

10. A control mechanism for a machine tool having a reciprocating tool carrying spindle comprising, in combination, a control rod supported for movement parallel to the axis of movement of said spindle, a pair of limit stops mounted on said rod in spaced relation, an intermediate stop mounted on said rod between said limit stops, and an actuator carried by the spindle and reciprocable therewith operative to engage said stops to shift the control rod and thereby control the reciprocation of the spindle, said actuator comprising a cylindrical member encircling the spindle and rotatable relative thereto to one position in which the actuator is effective to operatively engage said intermediate stop and to another position in which the actuator is ineffective to operatively engage said intermediate stop.

11. A control mechanism for a machine tool having a reciprocating tool carrying spindle comprising, in combination, a control rod supported for movement parallel to the axis of movement of said spindle, a pair of limit stops mounted on said rod in spaced relation, an intermediate stop mounted on said rod between said limit stops, and an actuator carried by the spindle and reciprocable therewith operative to engage said stops to shift the control rod and thereby control the reciprocation of the spindle, said actuator comprising a cylindrical member encircling the spindle and rotatable relative thereto to one position in which the actuator is effective to operatively engage said intermediate stop and to another position in which the actuator is ineffective to operatively engage said intermediate stop, and means cooperating with said member in all positions of the reciprocating spindle operable selectively to rotate said member to either position.

12. A control mechanism for a machine tool having a reciprocating tool carrying spindle comprising, in combination, a control rod supported for movement parallel to the axis of movement of said spindle, a pair of limit stops mounted on said rod in spaced relation, an intermediate stop mounted on said rod between said limit stops, and an actuator carried by the spindle and reciprocable therewith operative to engage said

stops to shift the control rod and thereby control the reciprocation of the spindle, said actuator comprising a cylindrical member encircling the spindle and rotatable relative thereto to one position in which the actuator is effective to operatively engage said intermediate stop and to another position in which the actuator is ineffective to operatively engage said intermediate stop, and spring actuated means cooperating with said member in all positions of the reciprocating spindle operative to maintain the member in said one position.

13. A control mechanism for a machine tool having a rotating and reciprocating tool carrying spindle comprising, in combination, a control rod supported for movement parallel to the axis of movement of the spindle, a pair of limit stops mounted on said rod in spaced relation, an intermediate stop mounted on said rod between said limit stops, an actuator carried by the spindle operative to engage said stops to shift the control rod and thereby control the reciprocation of the spindle, said actuator comprising a cylindrical member rotatably supported on the spindle and reciprocable therewith, and means for holding said member against rotation with the spindle to render the actuator effective to engage said intermediate stop and one of said limit stops alternately whereby the spindle is reciprocated through a series of working strokes.

14. In a honing machine, in combination, a tool carrying member, hydraulic means for reciprocating said member, valve means for controlling said reciprocating means, control means for said valve including a rock shaft adapted to be automatically actuated incident to said spindle approaching the limit of its stroke, and means for modifying the action of said control means to shorten the stroke of said spindle comprising a manually operable member loosely mounted on said shaft, and disengageable clutch means operatively connecting said member with said shaft whereby said member is enabled to actuate said shaft.

15. In a honing machine, in combination, a tool carrying member, hydraulic means for reciprocating said member, valve means for controlling said reciprocating means, control means for said valve including a rock shaft adapted to be automatically actuated incident to said spindle approaching the limit of its stroke, and means for modifying the action of said control means to shorten the stroke of said spindle comprising a member loosely mounted on said shaft and having a disengageable operative connection with the shaft, a second member loosely mounted on said shaft adjacent said first member, manually operable means for rotating said second member relative to the shaft, and means yieldably connecting said members for transmitting the rotational movement of said second member to said shaft to actuate the same, said connecting means absorbing the shock incident to the automatic actuation of the shaft.

16. In a holding machine, in combination, a tool carrying member, means for reciprocating said member, control means for said reciprocating means including a control rod movable between two control positions, spaced stop elements mounted on said rod, an actuating member carried by said member operative to engage said stop elements and thereby shift the control rod from one position to the other alternatively incident to the reciprocation of said member, and means for shifting said control rod from one

- position toward the other position independently of said actuating member to shorten the stroke of the reciprocating member comprising a manually operable element having a yielding disengagable connection with said control rod. 5
17. A control mechanism for a machine tool having a reciprocating part comprising, in combination, a control rod supported for movement parallel to the reciprocatory path of said part, 10 a pair of limit stops spaced longitudinally of said rod, an intermediate stop interposed between said limit stops, a two-position actuator carried by said reciprocating part, said actuator being effective in one position to operatively engage either said 15 intermediate stop or said limit stops and effective in the other position to engage only said limit stops to actuate the control rod, and means for shifting said actuator from one position to the other. 20
18. A control mechanism for a machine tool having a reciprocating part comprising, in combination, a movable control element supported adjacent said part, a pair of limit stops adjustably mounted on said element in spaced relation, an 25 intermediate stop adjustably mounted on said element between said limit stops, a two-position actuator carried by said part and reciprocable therewith, said actuator being operative in one position to engage either said limit stops or said 30 intermediate stop and in the other position to engage only said limit stops to actuate the control element, and non-reciprocating means for moving said actuator from one position to the other while said part is reciprocating. 35
19. In a honing machine, in combination, a tool support, a work support, means for reciprocating one of said supports relative to the other support to cause the tool to operate upon the work, control means for said reciprocation means including 40 a solenoid adapted when energized to render said reciprocating means operative to reciprocate said one support and adapted when deenergized to interrupt the operation of the reciprocating means, 45 first and second energizing circuits for said solenoid, a holding circuit for the solenoid, a manually operable switch effective when actuated to complete said first energizing circuit to energize said solenoid and thereby initiate the operation 5 of said reciprocating means, a switch operable by said solenoid for completing said holding circuit to hold the solenoid energized and thereby continue the operation of said reciprocating means independently of said manually operable switch, 10 and a second manually operable switch effective upon actuation to complete said second energizing circuit and to disable said holding circuit whereby to effect operation of said reciprocating means only while the second switch is actuated. 15
20. In a honing machine, in combination, a tool support, a work support, hydraulically operated means for moving one of said supports toward and from the other support to cause the tool to operate upon the work, a source of pressure fluid, 20 control means including a solenoid adapted when energized for rendering said source effective to supply pressure fluid to said hydraulic means for moving said one support and adapted when deenergized to interrupt the supply of pressure fluid, 25 to said hydraulic means to stop the support, first and second energizing circuits for said solenoid, a holding circuit for the solenoid, a manually operable switch in said first energizing circuit operative when actuated to energize said solenoid and 30 thereby initiate the operation of said hydraulic means, a switch in said holding circuit operable on energization of said solenoid to hold the solenoid energized and thereby continue operation of said hydraulic means independently of said manually operable switch, and a second manually operable switch in said second energizing circuit operative when actuated to energize the solenoid and to disable said holding circuit to effect operation of said hydraulic means only while said 35 second switch is actuated. 40

ALBERT M. JOHNSON.
